UNITED STATES PATENT OFFICE.

CHARLES KEIGHLEY AND ARLOND H. BLAISDELL, OF VINELAND, NEW JERSEY, ASSIGNORS TO SAID KEIGHLEY.

SHOE-HEEL-BURNISHING MACHINE.

SPECIFICATION forming part of Letters Patent No. 269,061, dated December 12, 1882.

Application filed October 16, 1882. (No model.)

To all whom it may concern:

Be it known that we, CHARLES KEIGHLEY and ARLOND H. BLAISDELL, citizens of the United States, and residents of Vineland, Cumberland county, New Jersey, have invented 5 certain Improvements in Shoe-Heel-Burnishing Machines, of which the following is a specification.

Our invention relates to certain improvements in attachments for shoe-heel-burnishing machines for the purpose of automatically imparting to the shoe holder or jack the movements necessary to carry the heel back and forth under the vibrating burnishing-tool, the 15 main difference between our invention and that described in the application of Charles Keighley, filed December 14, 1881, being that in the present case the attachment is so constructed that it can be readily applied to the 20 machines as now in use, and the devices for operating the jack being such that there is a more effective action of the burnishing-tool upon the hollow of the heel than in the former case.

25 In the accompanying drawings, Figure 1, Sheet 1, is a side view, partly in section, of a heel-burnishing machine with our improvements; Fig. 2, Sheet 2, a side view, partly in section, of part of Fig. 1, but looking in the 30 opposite direction; and Fig. 3, an end view of part of Fig. 2, looking in the direction of the arrow.

A is the central standard or column of the machine, having at the rear a projecting 35 bracket, B, on which are formed bearings for the driving-shaft D, the latter having the usual belt-pulleys, and being furnished with a crank-wheel, E, the pin of which is connected by a rod, E', to the short arm of the lever F. The 40 long arm of this lever carries the toothed segment, which gears into a pinion on the tool-shaft G, so that as the lever is vibrated a partial rotary movement will be imparted to said shaft, and the tool will be carried back and 45 forth around the heel of a shoe clamped in the jack H, the latter being hung to a stud on the front of the machine, so as to be free to vibrate.

In the above-mentioned application of 50 Charles Keighley mechanism was shown which derived its motion from the shaft D of the ma-

chine and served to vibrate the shoe-carrying jack so as to cause all portions of the heel to be presented to the action of the burnisher; but the mechanism there shown required such 55 changes in the machines as built that the alterations could not be readily effected in the shops where the machines were located.

In carrying out our present invention we make no change in the usual machine, except 60 the formation of openings x in the standard A and a central opening in the stud b, to which the lever F is hung, these openings being adapted for the passage of a rod, d, the front end of which is connected by a link, e, to the 65 shoe-carrying jack H, the rear end of the rod being connected by a rod, f, to a slotted arm, g, which projects from a pinion, h, the spindle of the latter having its bearing in a projection on a frame, m, which is secured to or forms 70 part of a frame, n, bolted to the bracket B of the machine, a further support for the frame m being afforded by a bar, p, which is bolted to the frame and to the stud b.

To bearings on the frame n is adapted a 75 shaft, k, one end of which carries a worm-wheel, s, the opposite end of the shaft having a cam-wheel, t, and the shaft being driven by a worm, v, which gears into the worm-wheel s, and is carried by a spindle adapted to bearings on the frame m, said spindle being driven from the shaft D through the medium of a suitable belt.

To the groove of the cam-wheel t is adapted a pin on the lower end of a rack, w, which engages with the pinion h, and is adapted to suitable guides on the face of the frame m. As the shaft k is rotated the cam-wheel t will impart a vertical reciprocating movement to the rack w, and the pinion h will be partially rotated, first in one direction and then in the opposite direction, the arm g being thus vibrated, and the vibrating movement transmitted to the jack H through the medium of the rod d, the extent of the movement being dependent 90 upon the adjustment of the pin of the rod f in the slot of the arm g.

The attachment, constructed as above described, can be applied to the ordinary machine without disturbing the same, the only 100 changes necessary being the formation of the openings x in the standard A, the substitution

of the bored stud *b* for the usual stud, and the bolting of the frame *n* upon the bracket *B*.

By means of the cam-wheel *t* and the mechanism shown the vibrating movement imparted to the jack *H* is differential—that is to say, there is a decrease in the speed of the movement at and near the mid-position, so that the burnishing-tool acts for a longer time upon the hollow or center of the heel than upon the top or bottom of the same, this being in accordance with the requirements of the case, as the center of the heel always needs more burnishing than the other portions.

The use of the peculiar heart-cam shown is not necessary for accomplishing this differential movement, however, as a plain cam, acting through the medium of differential gearing, will effect the same result.

We claim as our invention—

1. The combination of the shoe-carrying jack *H* of the machine, the tool-carrying shaft, and the lever *F* for operating the latter, with a rod, *d*, connected to the jack and passing through the stud on which the lever *F* vibrates, as set forth.

2. The combination of the jack *H*, the tool-

carrying shaft, and the lever *F*, with the rod *d*, passing through the stud on which the lever vibrates, and a frame, *m n*, secured to the bracket *B* of the machine and carrying the mechanism for operating the rod, whereby the ready adaptation of the attachment to the machine is effected, as set forth.

3. The combination of the tool-carrying shaft and the jack *H* with mechanism, substantially as described, for imparting a differential vibrating movement to said jack, as set forth.

4. The within-described jack-operating attachment, comprising the rod *d*, frame *m n*, shaft *h*, with worm-wheel *s*, and cam-wheel *t*, rack *w*, pinion *h*, arm *g*, and spindle carrying the worm *v* and driven from the main shaft *D*, as set forth.

In testimony whereof we have signed our names to this specification in the presence of 45 subscribing witnesses.

CHARLES KEIGHLEY.

ARLOND H. BLAISDELL.
